STITCHED FABRIC

Hans Diem, Neuchatel, Switzerland, assignor to
the firm Edouard Dubied & Cie. Société Ano-
nyme, Neuchatel, Switzerland

Application February 23, 1935, Serial No. 7,813
In Switzerland February 27, 1934

1 Claim. (Cl. 66—190)

This invention relates to looped fabrics which may be knitted in a simple manner or knitted by frame, the two faces of the fabric being dissimilar by the use of different yarn formations, viz., "stitches" and "stitches drawn through loops" that are intermeshed in such manner that the capability of the fabric of remaining true to form is increased and the elasticity of the same is reduced more or less depending on whether the fabric is required to stretch or to remain true to the original form at all times, but so that the fabric is nevertheless light and pliant, whereby the applicability of the fabric in the manufacture of garments of various kinds is considerably increased. By the distinction as made between "stitches" and "stitches drawn through loops" is intended to be brought out that in knitting fabrics of this kind "stitches" that is, yarn formations each consisting of a full needle loop and two halves of a sinker loop are used in combination with "stitches drawn through loops", each of the latter yarn formation consisting of a superposition of two complete loops of stitch-shape, i. e. stitches, which are slid one over the other, so that the loop first formed straddles the loop last formed.

The hitherto known looped fabrics knitted in a simple manner or by frame have the drawback of being too highly elastic in all directions and thus lacking a requisite resistivity against stretching, so that garments made of such fabrics are prone to change their shape particularly in the longitudinal direction of the garment.

According to this invention, a looped fabric similar to knitted ribbed fabrics with or without weft threads inserted between rows of yarn portions formed on opposite needle rows of the two fabric faces is provided, the fabric comprising on one face stitches that are each drawn through a loop by means of at least one needle, and at corresponding points on the other face wider stitches and wider stitches drawn through loops of equal width respectively formed by conjoint action of at least two adjacent needles and passed over to said corresponding stitches drawn through loops of smaller width.

By means of the thus obtained systematic arrangement of stitches and stitches drawn through loops of smaller width as well as wider stitches and stitches drawn through loops, in one and the same row, an irregular net-work is formed onto which each weft thread is first deposited and by effect of the interknitting operation is caused to change its stretched shape to a sinuous shape. Furthermore, this fabric, for both faces

of which by means of the invention a porous body is obtained, presents a patterned face of a nature similar to that of woven fabrics, and the other face of the fabric being of a nature as typical for stitched fabrics. Moreover, an elastic resiliency of the fabric ensues, particularly in the direction transversely of the weft, which resembles that of a genuine knitted fabric.

Hereinafter an example of the fabric according to the invention is described by taking reference to the accompanying drawing, in which

Figs. 1 and 2 each show the right and back face of a fabric respectively which compared to stitches of usual width (by being formed on a single needle) contains stitches and stitches drawn through loops of at least twice this width that were transferred over to stitches drawn through loops of usual, thus smaller width, after a weft thread had been inserted between the wider and smaller stitches drawn through loops or wider stitches and smaller stitches drawn through loops respectively, the yarn formations combined by transference then being knocked over, whereby the weft thread is bound in the fabric, that is, locked against longitudinal displacement, and the

Figs. 3 to 5 each illustrates schematically different consecutive working stages during effecting the looped fabric depicted in the Figs. 1 and 2.

In the drawing, the numeral 1 refers to rib 30 stitches drawn through loops of usual width, whereas by 2, 3 two interknitted complete loops, i. e. rib stitches of at least twice the usual width, each consisting of a complete loop 3 over which a previously formed complete loop 2 is slid so 35 as to straddle the loop 3, are designated. The superposition of the complete loops 2 and 3 may also be described as being effected by drawing the loop 3 through the loop 2. 2' refers to stitches of twice the usual width which stitches are how 40 ever not interknitted with a similar stitch or complete loop before being passed over. 4 represents the weft thread, 5 and 6 needles of one row of needles, and 7 to 14 needles of the other row of needles of the opposite needle bed.

The successive rows of horizontal meshes indicated in the Figs. 1 and 2 are each composed of stitches and stitches drawn through loops of larger width than usual that alternate in patterning order and that were intermeshed by 50 transference with stitches drawn through loops of usual width prior to a weft thread was inserted between the wider stitches and stitches drawn through loops that had been formed on one needle bed, and the stitches drawn through 55

loops of usual width that had been formed on the opposite needle bed. By knocking over the meshes, as combined of said oppositely disposed yarn formations by each transference, the weft threads were securely bound in the fabric and thus actually locked against longitudinal displacement relative thereto. This fabric can, by way of example, be produced in a knitting machine with two oppositely disposed needle beds as follows (Figs. 3 to 5):

It is assumed that from the start the cam slide is positioned on the left of the machine and that in the hooks of the needles 5 and 5, schematically indicating the lower needle bed which may be the front needle bed of the machine, stitches 1 drawn through loops of usual width formed from the knitting thread are inserted, whereas the hooks of the needles 1 to 14 of the opposite or rear needle bed are devoid of either stitches or stitches drawn through loops. Now, if in a known manner a double needle lock cam slide is traversed across the needle beds from left to right in these figures, by means of ordinary cam portions of the right hand needle lock, only on the needles 5 stitches 1 drawn through loops of usual width are formed again from this thread, but in a fresh length thereof and on oppositely disposed pairs of adjacent needles 1, 8; 9, 10; 11, 12; 13, 14 of the rear needle bed stitches 2 and 2' wider than usual are formed from the same length of this thread (Fig. 3). This explains why in this figure, which, as will be remembered, is only a schematic illustration, the stitches 1 drawn through loops on the needles 5 are connected by a continuous thread portion with the loops 2 and 2', whereas the stitches 1 drawn through loops on the needles 6 are not shown to be connected. The formation of stitches wider than usual from the knitting thread is accomplished in a similar manner as that of stitches of ordinary width by causing, by means of retracting cams of the corresponding needle lock, two adjacent needles of the rear needle bed to draw out one and the same thread loop, by conjoint movements, in this thread which is then fed across the hooks of the respective needles. This drawing out of stitches wider than usual is rendered possible by the thread, at the point in the length thereof where such a loop is formed, bearing against the corresponding tine of the knock-over cam of the respective needle bed, in which way this tine holds fast the middle portion of the wider stitch being formed, while on both sides of this tine the thread is pulled into the guideways of the two adjacent needles employed.

The stitches 2 being originally exactly equal to the stitches 2' are changed to stitches drawn through loops prior to their transference to the needles of the front needle bed, whereas the stitches 2' remain unchanged. This is accomplished by means of ordinary cam portions of the left part of the cam slide during passing the slide from right to left, while in cooperation with a known jacquard device, in accordance with a certain pattern, on the pairs of needles 7, 8 and 13, 14 fresh stitches 3 are formed and interknitted with the stitches 2, already held by these pairs of needles to stitches drawn through loops 2, 3 of a width larger than usual (Fig. 4). During the same traverse of the cam slide, by the left part thereof, stitches 1 drawn through loops of usual width are again knitted on the needles 5 of the front needle bed.

Thereupon, between the stitches 1 drawn through loops of usual width on the front needle bed and the wider stitches drawn through loops 2, 3 and the wider stitches 2' respectively on the rear needle bed a weft thread 4 is inserted. This is accomplished by moving, during the same traverse of the slide from right to left, a thread guide across the open meshes still held by the needles 5 and the opposite needles 7, 8, 9, 10 and so forth and depositing the weft thread supplied by this thread guide on the net or mesh-work thus formed. This mesh-work is irregular due to the alternation of wider stitches 2' with wider stitches drawn through loops 2, 3 in patterning order. Subsequently, during the next traverse of the slide from left to right the stitches 2' and the stitches drawn through loops are each passed over to a needle hook of an opposite needle 6 and deposited thereon in addition to the stitch 1 drawn through a loop already held by the respective needle 6 (Fig. 5), and finally the superposed stitches are knocked over to the left. The transference of the stitches and stitches drawn through loops wider than usual is effected by advancing the pairs of needles 7, 8; 9, 10; 11, 12; 13, 14 and so forth in their respective guideways into their highest positions, so that these stitches and stitches drawn through loops are held at a certain height above the needle beds. In the front needle bed the needles 6 are advanced into a median position so that the hooks of these needles are passed through opposite wider stitches and stitches drawn through loops. Thereupon the needles 7, 8; 9, 10 and so forth are retracted into initial position. During this movement the wider stitches and stitches drawn through loops carried by the latter needles close the correlated needle latches by sliding across the same and then enter the hooks of the opposite needles 6. This transferring operation is illustrated and more explicitly explained in my copending application Ser. No. 750,325 (Patent No. 2,059,682).

The same working cycle is then repeated except that this time on the one needle bed with the needles 6 and on the other needle bed with the needles 8, 9; 10, 11 and so on, stitches and stitches drawn through loops of usual width alternating with wider patterning stitches and stitches drawn through loops are knitted.

In the thus produced looped fabric the weft threads are inserted in sinuous shape, due to the network being irregular for the reason stated above, in order to be subsequently firmly bound in the knitted fabric by transference of the wider stitches and loops.

This sinuous shape being caused merely by adjacent mesh portions varying in shape, it will be seen that the amplitudes of the weft thread undulations equal substantially only the thickness of thread.

By incorporating a weft in knitted goods of the particular net structure as obtained by means of the invention a looped fabric results which on the one hand presents the same aspect, texture and capability of remaining true to form as woven fabrics and on the other hand is provided with a suppleness, porosity and an elastic resiliency in the direction transversely of the weft equalling genuine knitted goods in respect to these qualities.

I do not limit myself to the particular size, shape, number or arrangement of parts as shown and described, all of which may be varied without going beyond the scope of my invention as shown, described and claimed.

What I claim is:

In a looped fabric similar to knitted ribbed fabrics having a succession of rows of meshes, individual rows comprising on one fabric face 5 stitches and stitches drawn through loops of at least twice usual width alternating in patterning

order and intermeshed by transference with stitches drawn through loops of smaller width from the opposite fabric face, and a weft thread enclosed by said opposite yarn formations from both fabric faces.

HANS DIEM.
